UNITED STATES PATENT OFFICE.

FRANK M. LEAVITT, OF SMITHTOWN, NEW YORK, ASSIGNOR TO E. W. BLISS COMPANY,
OF BROOKLYN, NEW YORK, A CORPORATION OF WEST VIRGINIA.

TURBINE.

1,088,081.

Specification of Letters Patent.

Patented Feb. 24, 1914.

Application filed July 15, 1912. Serial No. 709,599.

To all whom it may concern:

Be it known that I, FRANK M. LEAVITT, a citizen of the United States, residing in Smithtown, in the county of Suffolk and State of New York, have invented certain new and useful Improvements in Turbine-Engines, of which the following is a specification.

This invention relates to nozzles such as are used in elastic-fluid turbines to discharge the motive fluid against the blades of the rotor, and particularly to that class employed in turbine mechanism for propelling automobile torpedoes wherein the nozzles are subjected to an intense and sudden rise of temperature in the compressed air which constitutes the motive fluid, due to the burning of a combustible therein. To provide a nozzle which will withstand this severe condition affords a very difficult problem. Its hollow form prevents forging it in one piece. If made of cast iron or steel it is liable to contain blow-holes which are exposed in the finishing, and it is often necessary to discard several castings after the expense of finishing has been incurred, before an apparently perfect one is produced, and even then it may contain a concealed imperfection rendering it worthless. Other cast metal, even phosphor bronze, is too readily fusible to withstand safely the intense heat to which the nozzle is subjected.

According to the present invention, the nozzle is made of steel by forging it in two pieces or sections, fitting and uniting them so as to leave a groove at their joint, and welding them together by fusing a like or similar metal into such groove, after which any necessary final finishing or machining may be done.

Figure 1 of the accompanying drawings is a view of the after part of an automobile torpedo, a portion of its shell being shown as broken away to disclose a part of the propelling mechanism, the latter appearing in central longitudinal section; Fig. 2 is a view of part of one of the bulkheads, also shown as having a broken away section to disclose one of the turbine rotors, and shows my improved nozzle in position to discharge the motive fluid against the rotor blades; Fig. 3 is a plan of the outer or discharge side of the nozzle plate; Fig. 4 is a side elevation of the nozzle plate; Fig. 5 a central longitudinal section of the nozzle showing

the manner in which the parts are joined; Fig. 6 a cross-section on the line 6—6 of Fig. 5; Fig. 7 a plan of the body portion of the nozzle; Fig. 8 a cross-section on the line 8—8 of Fig. 7; Fig. 9 a plan of the inner side of the nozzle plate; and Fig. 10 a cross-section on the line 6—6 of Fig. 5, showing the parts in position to be welded.

Referring to the drawings in detail, the letter A (Fig. 1) indicates the body of an automobile torpedo, B, B' the propellers, and C, C' the propeller shafts.

D designates, generally, a train of gears which are arranged to rotate the propeller shafts in reverse directions, and which are actuated by the turbine rotors E, E'.

The letter F denotes a bulkhead which is provided with an aperture G. This aperture is covered by the nozzle H which is bolted to the bulkhead, and a portion of which extends therethrough so as to bring the nozzle ducts into proximity to the blades of one of the rotors E.

Having thus briefly shown the application of the nozzle in automobile-torpedo propelling mechanism, I will now describe the nozzle itself and its construction in detail:

In order to make the nozzle of forged metal, I form it in sections (preferably two steel drop-forgings), one section, indicated by the letter I, forming the body portion having a longitudinal hollow a to form the chamber or cavity in the nozzle, and having an inlet pipe-connection b and a flange c by which it is attached to the bulkhead; the other section J being the nozzle plate which is provided with a plurality of extending ducts e to discharge the motive fluid against the blades of the rotor. The body portion is milled or otherwise initially finished on the surface f (stock being allowed for final finishing after the parts are joined) and is recessed so as to form a shoulder g, the surrounding wall h of which is beveled, as shown in Figs. 5, 6, 7, 8 and 10.

The ducts e having been cut in the nozzle plate and the necessary finish given to that portion of the plate indicated by the letter i which extends within the hollow of the body portion, the surface j is finished, and the edge k beveled similarly to the wall h of the body portion, but in the reverse direction, so that when the two parts are placed together as shown in Figs. 5, 6 and 10, the

surface *j* of the nozzle plate will rest upon the shoulder *g* of the body portion, leaving a V-shaped groove extending around the nozzle plate between the two parts. Into 5 this groove (while the parts are in the inverted position shown in Fig. 10) metal is fused so as to weld the two parts of the nozzle firmly together, after which those outer surfaces of the nozzle that require 10 further finishing are machined or filed. The welding is best performed by first heating the two sections, then fusing the welding metal from a rod into the groove at opposite ends, then at successive intermediate 15 points, and finally flowing it through the entire groove. The welding metal (steel or iron, is most effectually fused by applying some form of intense localized heat, such as that of an oxygen-acetylene flame, the flame 20 being first played upon the sections to pre-heat and expand the welding surfaces.

I claim as my invention:

1. A nozzle for elastic-fluid turbines, comprising two forged sections, one being embedded in and welded to the other.
2. A forged nozzle for elastic-fluid turbines, comprising a recessed body portion, and a nozzle plate set into said recess and welded to the body portion.
3. A nozzle for elastic-fluid turbines, composed of two sections, one comprising a body portion and the other a nozzle plate, said

nozzle plate being embedded in said body portion and fused thereto.

4. In a forged nozzle for elastic-fluid turbines, a body portion having a hollow within its margin, recessed to form a shoulder, and a plural-duct nozzle plate fitted into said recessed portion and resting against said shoulder, the two parts being 40 united by welding.

5. A nozzle for elastic-fluid turbines, comprising a forged, hollowed body portion provided with a flange for securing it in position and with an inlet opening into the 45 hollow thereof, and a forged, elongated nozzle plate, welded to said body portion so as to cover the hollow therein, said nozzle plate having a plurality of laterally distributed ducts.

6. A turbine nozzle of forged steel having a flanged, hollowed body portion, and a plural-duct nozzle plate.

7. A turbine nozzle of forged steel having a hollowed body portion and a plurality of 55 outlet ducts.

In witness whereof, I have hereunto signed my name in the presence of two subscribing witnesses.

FRANK M. LEAVITT.
